COMBINED BIB AND TRAY FOR BABIES

Albina L. Cowins, Port Reading, N. J.

Application September 29, 1955, Serial No. 38,149

Term of patent 7 years

(Cl. D3—26)

Figure 1 is a front view of a combined bib and tray for babies showing my new design.

Fig. 2 is a side view thereof as it would appear in use. The broken line showing in Fig. 2 is merely for convenience of illustration.

I claim:

The ornamental design for a combined bib and tray for babies, as shown and described.
